UNITED STATES PATENT OFFICE.

WILLIS C. MUNRO AND FRANK X. MUDD, OF CINCINNATI, OHIO.

COPY-HOLDER FOR TYPE-WRITING MACHINES.

SPECIFICATION forming part of Letters Patent No. 368,962, dated August 30, 1887.

Application filed April 25, 1887. Serial No. 236,036. (No model.)

To all whom it may concern:

Be it known that we, WILLIS C. MUNRO and FRANK X. MUDD, citizens of the United States, residing at Cincinnati, in the county of 5 Hamilton, in the State of Ohio, have invented a certain new and useful Improvement in Copy-Holders for Type-Writing Machines, of which the following is a specification.

Heretofore operators upon type-writing machines have held their copy while writing in copy-holders placed at the side and independent of the type-writing machine. By this arrangement the operator is obliged to turn his head constantly from the key-board to the 15 copy. This naturally retards the speed of writing, besides being very tedious for the operator.

The object of our invention is to furnish a copy-holder for type-writing machines by 20 which the copy is brought immediately behind the key-board, so that the operator can readily see both copy and key-board without moving the head. This greatly adds to the speed and ease of operation.

25 A skillful operator by using one of our improved copy-holders can write continuously.

In the accompanying drawings, Figure 1 is a front view of a type-writer, showing one of our improved copy-holders in position. Fig. 30 2 is a front view of the copy-holder detached from the type-writer. Fig. 3 is the spring-hook of the line-marker reversed.

35 A is the front portion of the frame of a type-writer, having the upright posts a' a' , the top plate, b , bearing the scale b' , the key-board d , and space-bar e .

40 B is a metal plate, having its lower edge bent upward to form a rest, c , for the copy, and a narrow projection, c' , from the upper edge bent downward to hold the note-book or copy firmly in position. The lateral projections g g are adapted to lap by the upright

posts a' a' , and are fastened to these posts by means of buttons f f , which are held firmly in position by thumb-screws f' f' . 45

l is a line-marker, which is attached to the rod m by a spring-hook, n , clasping the rod in such a way as to permit the line-marker to slide up and down the rod, and to hold it in any position by tightly grasping the rod. The 50 line-marker can be readily detached from the rod by unclasping the hook n .

We do not confine our invention to any particular material, for the copy-holders may be made of metal, pasteboard, wood, wire, &c., 55 and may be adapted to all type-writing machines by slight alteration in form.

We claim—

1. A copy-holder in a type-writing machine, adapted to be placed between the key-board 60 and the impression-roller.

2. In combination with the frame of a type-writing machine, a plate, B , provided with rest c and projections g g , substantially as and for the purpose specified. 65

3. The combination, with the frame of a type-writing machine, of a detachable plate, B , having its lower edge bent upward to form a rest, c , and a rod and line-marker sliding thereon, substantially as and for the purpose 70 specified.

4. In combination, the frame of a type-writing machine and a plate having its lower edge bent upward to form a rest for the copy, in the manner and for the purpose specified. 75

5. In combination, the frame of a type-writing machine and a plate provided with projections whereby the plate is attached to said frame, as specified.

WILLIS C. MUNRO.
FRANK X. MUDD.
